United States Patent Office

Des. 214,873
Patented Aug. 12, 1969

214,873

BOTTLE OR SIMILAR ARTICLE

Victor Koenigsberg, Franklin Square, N.Y., assignor to Colgate-Palmolive Company, New York, N.Y., a corporation of Delaware

Filed Nov. 21, 1967, Ser. No. 9,489

Term of patent 14 years

Int. Cl. D9—01

U.S. Cl. D9—83

FIG. 1

FIG. 2

FIG. 4

FIG. 1 is an elevational view of a bottle embodying my new design;

FIG. 2 is an elevational view thereof as seen from the side opposite FIG. 1;

FIG. 3 is a top plan view; and

FIG. 4 is a bottom plan view thereof.

The plain area in the lower band of ornamentation does not extend beyond the area shown in FIG. 1.

I claim:

The ornamental design for a bottle or similar article, as shown and described.
